UNITED STATES PATENT OFFICE.

GEORGE S. BRUSH, OF ZANESVILLE, OHIO.

DESIGN FOR A CLOCK CASE.

Application filed May 2, 1924. Serial No. 9,469. Term of patent 7 years.

To all whom it may concern:

Be it known that I, GEORGE S. BRUSH, a citizen of the United States, residing at Zanesville, in the county of Muskingum and State of Ohio, have invented a new, original, and ornamental Design for Clock Case, of which the following is a specification, reference being had to the accompanying drawing, forming part thereof.

Fig. 1 is a perspective view of the design.
Fig. 2 is a vertical central section of the same, the clock dial and operating parts being omitted.

I claim:

The ornamental design for a clock case as shown.

GEO. S. BRUSH.
